SHADE AND CURTAIN SUPPORT

Filed July 18, 1927

Lula H. Robinson

INVENTOR.

BY Ernest A. Wood

ATTORNEY.

UNITED STATES PATENT OFFICE

LULA H. ROBINSON, OF DALLAS, TEXAS

SHADE AND CURTAIN SUPPORT

Application filed July 18, 1927. Serial No. 206,464.

This invention relates to window and door draperies and fixtures and it refers more particularly to certain new and useful improvements in combination shade and curtain brackets and mountings, and the principal object of the invention resides in the provision of a mounting of such nature as to enable the shade and curtains to be moved to points of advantage with respect to the window, as for convenience in rearranging the draperies and supplying suitable ventilation to the room through the upper sash while the interior of the room is unexposed through the lower sash.

Another and important object of the invention resides in the provision of novel means for raising and lowering the assembly upon the window, and the means for holding the assembly in adjusted position thereon.

Broadly, the invention comprehends the provision of an article of utility, and of such compact and economical construction as to enable it to be used effectively in hotels, hospitals and similar buildings, as well as domestically, especially in view of its facilities for ready adjustment, by which the draperies may be easily removed and replaced.

With the foregoing objects as primary, the invention has particular reference to its novel features of construction and operation of parts, by which the foregoing objects are attained and which will become manifest as the description proceeds, when taken in connection with the accompanying drawings wherein:

Figure 1 represents a plan view of a combined curtain rod and window shade support constructed according to the present invention.

Figure 2 is a front view thereof.

Figure 3 is a fragmentary end view of the support showing the rear side of the adjustable hanger.

Figure 4 is a detail view showing the upper end of the lifting rod.

Figure 5 is a side view of Figure 4.

Figure 6 is a detail view of one of the combination brackets, and

Figure 7 is a modified form of bracket shown in Figure 6.

Continuing now more in detail with the drawings, it may be first stated that the application to a window, a form of support whereby the latter will be capable of vertical adjustment with respect to the opening is a well known precedent and the present invention claims no novelty in this regard, but does claim as novel the hanger, adjustment mechanism and combined adjustable brackets for the curtain rods and shade.

In Figure 1 especially the preferred type of track 1 is shown, which is arranged to be secured to opposing sides of a window, and has punched at spaced intervals therein projections 2.

The hanger 3 is designed so as to be extensible, being composed of hollow end pieces 4 and core 5 extending into the latter. The outer end of the end pieces 4 have affixed thereto sides 6 slidably engaging the tracks 1 in the manner shown clearly in Figure 1, to allow vertical movement of the hanger 3 and its associated elements, later described.

Slides 7 are connected to the hanger 3 adjacent to the ends of the latter, by means of braces 8. These slides are adapted to carry the combination brackets 9, hereinafter referred to in detail, so as to permit of independent adjustability of the latter horizontally in the manner shown.

With reference especially to the means for holding and releasing the hanger to effect its adjustment upon the window, reference is made to Figures 1 and 3, especially the latter. Latches 10 are shown in dotted lines in Figure 3, which are held normally in extended position under pressure of the springs 11, so as to engage the projections 2 carried by the tracks, thus to hold the hanger 3 in suspension in each adjusted position. The portions of the latches 10 engaging the projection 2 are reduced in order to provide a stop by the portion shown in dotted lines in Figure 3. A link 12, integral with the latch extends toward the center of the hanger and is longitudinally slotted at *a*, and in which slides a screw 13, carried by a link 14 therebelow. This latter link extends nearer the

middle of the hanger where it is turned abruptly outward to form a grip 15. Adjustability as to length of the latch operating links 12 and 14, to correspond with the width of a window is obtained by loosening the screw 13 and sliding the link 12 to the proper position and again tightening the screw. The screw 16 is mounted in the short slot 17 in the link 14 to limit the movement of the latter and consequently the latches 10.

10 The springs 11 adapted for urging the latches 10 into engagement with the projections 2 of the tracks, are mounted upon pins 18, and being interposed between stops 19 and 20, connected to the latch 10 and hanger 3 respectively, cause the latch to be constantly under pressure, being withdrawn by moving the grips 15 together. The stop 20 likewise functions as a guide for the pin 18.

20 While it is immaterial what design of bracket is employed with the described hanger, the improved type of combination bracket as illustrated in Figures 6 and 7 is preferred. The bracket shown in Figure 6 is apertured 25 at *b* as shown to support the end of the shade roller, indicated at 21 in broken lines. The same reference character denotes the window shade in Figures 1 and 2. The bracket 9 has a tail portion 22 turned at right angles with 30 respect to the bracket proper which slides into the slide 7 on either end of the hanger 3 and fastened in adjusted positions by a set screw 23. The form of bracket shown in Figure 6 does not permit of independent adjustment of the shade support as apparent. Therefore, in cases where such adjustment is 35 desired, the form of bracket shown in Figure 7 is provided, which departs from the principle of the former type of bracket only in the 40 addition of the shade bracket attachment 24, which is arranged so as to have independent horizontal adjustment with respect to the rod supporting bracket 9 and hanger 3. The brackets 9 are shown with slots for supporting 45 the rods 25 shown in Figures 1 and 2, but with only slight alterations may be equipped to support curtain poles and other drapery accessories without departing from the principle involved.

50 In cases where the hanger 3 is installed upon a low window, such as in residences, the grips or lugs 15 may be operated manually to withdraw the latches 10 in adjusting the hanger 3 upon the window, but where the 55 windows are high and inaccessible in this regard, an adjusting pole such as shown in Figures 4 and 5 is provided whereby no difficulty may be encountered in effecting adjustment of the hanger. This pole is designated by 60 the character 26 and has upon its end a bifurcated head 27. A tongue 28 extends outward from the head and is turned abruptly upward, and the forks at the top of the head are turned outward at 29 to engage the top 65 of the hanger to pull the same downward.

The deflected edges at 30 are adapted to be moved upward against the lugs 15 on the hanger to urge the same together to release the latches, simultaneously pushing or pulling the pole to raise or lower the hanger by 70 the tongue 28 or forks 39 respectively.

75 The construction described lends to the hanger the required rigidity, yet maintaining the compactness and simplicity necessary to present a neat and tidy appearance on a window.

80 Manifestly, the construction shown is capable of considerable modification, and such modification as is in keeping with the appended claims is considered within the spirit 85 of the invention.

What is claimed is:

1. In a shade and curtain hanger, tracks, an extensible shade and curtain carrier, 85 sliding track engaging latches on the carrier, longitudinally slotted links secured to the inner ends of the latches, a pin secured at one end to each latch, a lug for each pin on the carrier receiving the opposite end of the pin, a spring encircling each pin and abutting 90 said lugs to tension the latches, a sliding link for each latch, means extending through the slots of the first named links for adjustably connecting the first named links to the sliding links, said sliding links having slots, 95 means secured to the carrier and extending through the slots of the sliding links to limit sliding of the latter, and operating grips on the inner ends of the sliding links.

2. In a shade and curtain hanger, tracks, 100 an extensible shade and curtain carrier, sliding track engaging latches on the carrier, links secured to the inner ends of the latches, spring pressed means for independently tensioning each of the latches connected thereto 105 and to the carrier, a sliding link for each latch, means to adjustably connect the first named links to the sliding links, means to restrict sliding of the sliding links, and operating grips on the inner ends of the sliding 110 links.

In testimony whereof I affix my signature.
LULA H. ROBINSON.
